DISPENSER FOR USE WITH AEROSOL CONTAINERS

C. James Corris, Camden, S.C., assignor to Warner-
Lambert Company, Morris Plains, N.J.

Filed July 2, 1973, Ser. No. 375,564

Term of patent 14 years

Int. Cl. D9—01

U.S. Cl. D6—95

Fig. 1

Fig. 2

FIG. 4

FIG. 3

FIG. 5

FIG. 6

FIG. 1 is a perspective view of a dispenser for use with aerosol containers showing my new design;

FIG. 2 is a front elevational view thereof;

FIG. 3 is a side elevational view thereof;

FIG. 4 is a rear elevational view thereof;

FIG. 5 is a top plan view thereof; and

FIG. 6 is a bottom plan view thereof.

I claim:

The ornamental design for a dispenser for use with aerosol containers, substantially as shown.
